DESIGN FOR A WALKING STICK

Eberly R. Ethington, Santa Monica, Calif.

Application May 8, 1946, Serial No. 129,450

Term of patent 3½ years

(Cl. D88—3)

To all whom it may concern:

Be it known that I, Eberly R. Ethington, a citizen of the United States and a resident of Santa Monica, California, have invented a new, original, and ornamental Design for a Walking Stick, of which the following is a specification, reference being had to the accompanying drawing, forming part thereof.

Referring to the drawing:

Figure 1 is a side elevational view of a walking stick, showing my new design;

Figure 2 is a front elevation of the device as viewed from the left of Figure 1; and

Figure 3 is a rear elevation, of the upper portion of the device, as viewed from the right of Figure 1.

I claim:

The ornamental design for a walking stick, as shown.

EBERLY R. ETHINGTON.
